UNITED STATES PATENT OFFICE.

ERNEST D. ANDERSON AND CARL BECKMANN, OF NEW YORK, N. Y., ASSIGNORS TO E. D. ANDERSON, INC., OF NEW YORK, N. Y., A CORPORATION OF NEW YORK.

PACKAGING MACHINE.

1,412,227.

Specification of Letters Patent. Patented Apr. 11, 1922.

Application filed November 4, 1920. Serial No. 421,756.

To all whom it may concern:

Be it known that we, ERNEST D. ANDERSON, a citizen of the United States, and resident of New York city, borough of Manhattan, county and State of New York, and CARL BECKMANN, a subject of Germany, and resident of New York city, county of Queens, New York, have invented certain new and useful Improvements in Packaging Machines, of which the following is a specification.

Our invention relates to improvements in machines for charging receptacles or cartons with goods and has for its principal object to remove a receptacle or carton in the event that the same is not charged or is only partly charged with the required amount of goods, to prevent such charged or partly charged receptacle or carton from being carried along with the fully charged receptacles or cartons.

In the form of machine illustrated in the accompanying drawings we provide means to support the receptacles or cartons in position to be charged with goods, means to charge the required goods in the receptacles, and means to extract or remove a receptacle from its support in the event that such receptacle is not charged with the required quantity of goods or number of articles. In the form of machine shown in the accompanying drawings we provide means to successively charge a receptacle or carton with two articles and means operating automatically to extract or withdraw the receptacle from its supporting means in the event that such receptacle should not be charged or should only be charged with one such article. It will be understood, however, that the mechanism hereinafter set forth may be adapted to charge the receptacles or cartons with any desired quantity of goods or number of articles and to extract receptacles or cartons in case any lesser quantity of goods or number of articles is charged in the receptacles or cartons or no charges be inserted.

Our invention comprises novel details of improvement that will be more fully hereinafter set forth and then pointed out in the claims.

Reference is to be had to the accompany-

ing drawings forming part hereof, wherein—

Fig. 1 is a plan view of a portion of a machine embodying our invention; Fig. 2 is a cross section substantially on the plane of the line 2—2 in Fig. 1; Fig. 3 is a cross section on the line 3—3 in Fig. 2; Fig. 4 is a cross section on the line 4—4 in Fig. 2; Fig. 5 is a cross section on the line 5—5 in Fig. 4; Figs. 6, 7 and 8 are detail cross sections on plane of line 8—8 in Fig. 1; Figs. 9 and 10 are enlarged detail cross sections on line 9—9 in Fig. 1; and Fig. 11 is an enlarged detail plan view of parts shown in Fig. 9.

Similar numerals of reference indicate corresponding parts in the several views.

The numeral 1 indicates the main frame of the machine which may be of any suitable construction. At 2 is indicated a support in the form of a conveyer for receptacles or cartons 3 to be charged, which conveyer may be in the form of an endless chain provided with receivers 2^a spaced thereon to receive and propel the receptacles 3. The conveyer 2 may be supported at opposite ends upon spaced sprocket wheels 4 carried by shafts 5 journaled in the main frame in any well known manner. Said conveyer may be driven in any desired manner, step by step. We have illustrated mechanism, such as a Geneva movement, for operating the conveyer, comprising an arm 6 on shaft 7 journaled in bearings on the main frame, which arm has a projection 8 to engage a Geneva member 9 on shaft 5. Shaft 7 is shown provided with a gear 10 in mesh with a pinion 11 on shaft 12 journaled on the main frame and provided with a pulley 13 receiving belt 14 from a suitable source of power. For each rotation of arm 6 the conveyer will be operated a step. The upper run of conveyer 2 may travel upon a longitudinal guideway 15 supported on the main frame, and bars or rails 16 supported by the main frame over the conveyer serve to retain the receptacles or cartons 3 in proper position on the conveyer as the receptacles are carried along by the latter. The receptacles or cartons 3 may be successively applied in the receivers of the conveyer by manual operation

or by any suitable or well known automatic devices adapted to deposit the receptacles in the receivers. In case the receptacles 3 are deposited in the receivers of the conveyer in collapsed condition said receptacles may be opened ready for charging by means of any suitable opening mechanism. An opener 17 is illustrated in Fig. 1 carried by a reciprocative rod 18 journaled in bearings on the main frame and which may be operated by an arm 19 connected with an arm 20 on a rock shaft 21 journaled on the main frame. Said shaft may be rocked by a crank arm 22 and link 23 actuated in any suitable manner, as by means of a bell crank 24 on shaft 25 journaled on the main frame. Link 26 connected with said crank has a projection 27 to be operated by a cam, which may be in gear 10, whereby for each 20 rotation of said gear the shaft 21 will be rocked back and forth. A spring 18^a cooperates with the opener 17 in connection with arm 19. Devices for operating the opener may be adopted substantially similar to those set forth in the patent to E. D. Anderson, No. 1,151,233, dated August 24, 1915.

The article or goods *a* to be charged into the open receptacles 3 may be supplied and fed to the receptacles in any suitable manner. In the accompanying drawings we have illustrated means to supply said articles and charge a plurality thereof into the open receptacles 3 as follows:—A hopper 28 (Figs. 2, 3 and 4) is shown supported in an inclined position adapted to contain the articles *a*. Said hopper is shown journaled at its lower portion at 29 upon uprights 30 on the main frame so that the hopper may be rocked. Said hopper is shown provided with laterally extending arm 31 connected with depending rod or link 32 operatively connected with a crank arm 33 carried by a shaft journaled on the main frame and connected with 45 a sprocket wheel 34 receiving a chain 35 from a drive sprocket 36 secured on shaft 5 whereby as said shaft is rotated the hopper will be rocked. Hopper 28 is shown provided with an inclined bottom 28^a to deliver articles therefrom to chute 37 which inclines downwardly over guide or block 38 supported upon the main frame by support 39 (Fig. 2). The upper end of the chute 37 is shown supported upon a rod 40 carried by uprights 30. The downwardly inclined bottom 28 of the hopper is shown separated at the middle portion and provided with interposed spaced bars 41 supported by cross pieces 42 carried by the hopper. A separating bar 43 at the bottom of the hopper between bars 41 divides at 43^a to provide two runways for the articles *a* from the hopper for discharging into two chutes 37 that respectively terminate over the corresponding block 38. In the example illus-

trated two articles *a* are to be charged into each receptacle or carton 3, one of said articles being charged in advance of the other, so that two blocks 38 are spaced apart along one side of the conveyer in position to oppose two receptacles 3 each time the conveyer is brought to rest. Over the bars 37^a of the chutes are longitudinally disposed rails 44 (Fig. 5) to prevent articles *a* from springing up out of position as they slide 75 down the chutes. Rails 44 may be supported upon the chute by means of strips 45 secured to the rails and having rods or the like 46 depending and secured to lugs or projections 47 at the side of a chute. Since 80 the chutes communicate with the delivery end of the hopper the articles *a* will be delivered from the hopper to the chutes as the hopper is rocked, and the articles will be shifted around in the hopper so that they 85 will slide therefrom into the chutes. At the lower end of the chutes means are provided for selecting the articles *a* for the receptacles 3 and charging the articles into said receptacles. At the lower end of each chute, associated with each block 38, is a rockable or rotative head 48 (Figs. 6, 7, and 8), shown having a curved periphery adapted to oppose the exit of articles *a* from the chute, and also shown having a passage or channel 49 to receive the articles *a* successively to be pushed therefrom towards the receptacles 3 when the latter are brought to rest successively opposite said heads. The heads 48 have end pivots 50 journaled in jaws or 90 supports 51 associated with guides or blocks 38. The heads 48 may be given rocking movement, timed with relation to the stopping of open receptacles 3 opposite the heads, by any suitable means. Heads 48 are 95 shown provided with crank arms 52 pivotally connected with depending rod 53, the lower ends of which rods are guided in guides 53^a carried by the main frame (Figs. 1 and 2). Each rod 53 is provided with a 100 projection 54 disposed in a cam-slot 55^a in a bar 55 guided to reciprocate in a guideway in or on support 39. The shape of slot 55^a is such that when bar 55 is in a retracted position rod 53 will have been moved to cause 105 head 48 to be rotated to bring its channel or passage 49 in register with the articles *a* in the corresponding chute 37 to receive an article (Fig. 6). An abutment or stop 56 is shown located on the side of head 48 adjacent to the conveyer and a receptacle thereon to temporarily retain an article *a* in passage 49. At such time said article in passage 49 will resist the advance of other articles in the chute, and when bar 55 is 110 moved to the right in Fig. 2 rod 53 will be moved downwardly to cause head 48 to rock a suitable distance to present said article *a* in passage 49 in position opposite the receptacle 3 to be pushed therein (Fig. 7). Slot 115

55^a is shown provided with a lower horizontal portion of sufficient length to permit the desired movement of bar 55 without then operating head 48. The several heads 48 5 operate approximately together to simultaneously register articles *a* in spaced heads 48 with spaced receptacles 3 on conveyer 2. At the time that the heads 48 have been moved to present the articles *a* in said heads 10 in position to enter the opposing receptacle 3 pusher or plunger 57 for each head is moved forwardly to push the article *a* from corresponding head 48 into the opposing receptacle 3, (Figs. 7 and 8). Pusher or 15 plunger 57 is pivotally connected with the corresponding bar 55 at 58 and is guided in a way 38^a in the corresponding block 38 to enter the passage 49 in the opposing head 48 (Figs. 6, 7, and 8). Bar 55 is pivotally connected by link 55^b with crank-arm 58 on rock-shaft 21. As said shaft is rocked the bars 55 and pushers 57 will be reciprocated together. The length of pushers 57 with 20 relation to slots 55^a of bars 55 is such that when said pushers and bars are moved in one direction, as to the right in Fig. 2, the bars will first cause operation of heads 48 to align their passages 49 with the pushers and a farther movement of bars 55 with the 25 pushers will cause the latter to pass through the corresponding passages 49 to eject articles *a* therefrom and push the latter into receptacles 3 (Figs. 7 and 8). On the return movement of said bars and pushers the 30 latter will be withdrawn from heads 48 just before the raised cam-like parts of slots 55^a cooperate with pins 54 to cause rods 53 to rise and return heads 48 to the article receiving positions. When the heads 48 are 35 out of article receiving position the lowermost articles *a* in chutes 37, by resting against the surfaces of said heads, will be retained in the chutes, but as soon as passages 49 have been brought to register with the chutes the lowermost articles will slide 40 from the chutes into passages 49 respectively to be stopped against abutments 56, and so on for each reciprocation of bars 55 and pushers or plungers 57. The devices 45 described provide means for separating the articles *a* from the bulk thereof, aligning the separated or selected articles with the receptacles 3 and charging the selected articles into the receptacles. 50

55 The receptacles may be charged with any desired quantity or number of goods or articles. In the example illustrated the charging means are adapted to feed one article *a* at a time into a receptacle, and with two of such charging means spaced apart each carton should be charged with two articles *a* one after another. The arrangement shown 55 is such that at the position A in Fig. 1 one article *a* will be fed into a receptacle (Fig. 7), and when such partly charged receptacle

has been stepped by the conveyer to position B is Fig. 1 another article *a* will be fed into said receptacle, the last fed article pushing the first fed article farther into said receptacle (Fig. 8). 70

Our invention enables the extraction from the conveyer of a receptacle 3 in case the latter is partly charged with the required goods or articles or in case it is not charged at all. In the form of invention illustrated 75 we utilize the full charge or the absence of such full charge in a receptacle as a determining factor in the extraction or non-extraction of such receptacle from the conveyer. To accomplish the aforesaid results 80 we have illustrated means as follows:—At a point along the conveyer designated by the letter C, Fig. 1, at a position where the conveyer comes to rest with charged receptacles, we locate receptacle extracting devices before the point of delivery of the finished receptacles from the conveyer. A reciprocative finger or feeler 60 is carried by a bar 61 on one side of the conveyer opposing a stop or abutment 62 on the opposite 85 side of the conveyer (Figs. 1, 9, 10 and 11). The stop 62 is shown carried by the guide-way 15. The bar 61 is shown guided to reciprocate along guide bars 63, 64 supported in horizontal position by upright 65 90 on main frame 1. When finger 60 and bar 61 are retracted to the dotted position shown in Figs. 9 and 10 the receptacles 3 may pass between said finger and the stop 62. Associated with finger 60 are grippers 100 66, 67, the inner ends of which oppose said finger to grip receptacles. Said grippers are shown pivotally supported at 68 upon projections 69 extending from bar 61. The outer ends of grippers 66, 67 are shown 105 connected by springs 70 with bar 61, tending to cause the inner ends of the grippers to approach finger 60. The grippers 66, 67 respectively have lateral pins or projections 66^a, 67^a adapted to encounter abutments 71, 72 shown carried by upright 65; (Figs. 9 and 10). The abutments 71, 72 are shown 110 provided with inclined portions 71^a, 72^a, to engage the pins 66^a, 67^a respectively to cause tilting of the grippers 66, 67 when 115 the grippers recede from the conveyer, as indicated in Figs. 9 and 10 in dotted lines. At 73, 74 are receptacle discharging stops, shown on opposite sides of the path of finger 60 (Fig. 11), to encounter receptacles carried 120 by said finger and the grippers to discharge the receptacles therefrom. Any suitable means may be provided to reciprocate the finger 60 and the grippers. We have shown a reciprocative bar 75 having a longitudinal 125 slot 75^a receiving a lateral pin 76 extending from bar 61 (Fig. 11). A spring 77 connected with bar 75 at 78 and with pin 76 (Fig. 9) serves to draw the bar 61 toward the left in the drawings to permit rod 75 130

to move independently of pin 76 for a limited distance. The rod 75 is shown pivotally connected with a rock arm 79 pivotally supported on the main frame by bracket 80, 5 said arm 79 being shown pivotally connected with a link 81. The link 81 is shown pivotally connected with a crank arm 82 secured on rock shaft 21. As said shaft is rocked the rod 75 will be reciprocated to reciprocate bar 61, the finger 60 and the grippers with it. 10

When the open receptacles or cartons 3 are brought to rest opposite the charging devices the latter will operate to charge the articles *a* into said receptacles. The conveyer will also bring the charged receptacles to rest opposite the devices to extract from the conveyer any uncharged or partly charged receptacles. When the conveyer stops a charged receptacle 3 between finger 15 60 and the stop 62 said finger will advance with grippers 66, 67, while the pushers advance to charge receptacles, and the finger will encounter an article *a* in the receptacle and push the same. The stop 62 will limit 20

25 the movement of article or articles *a* within the receptacle whereby further progress of finger 60 will be arrested by the article or articles *a* opposing the same, thereby to prevent the grippers 66, 67 from engaging receptacle 3, see Fig. 9. The bar 75 will continue to the end of its stroke, the spring 77 then expanding, the slot 75^a of bar 75 sliding on pin 76. The said operations permit finger 60 to remain temporarily pressed against article *a* in the receptacle. Upon the return stroke of bar 75 it will encounter pin 76 and push bar 61, finger 60 and the grippers away from said receptacle and pushers 57 will recede from the receptacles. 30

40 When the finger and pushers are away from the receptacles the latter will be advanced by the conveyer. Similar operations will occur each time the conveyer brings a properly charged receptacle to rest opposite a finger 60, the charged receptacles being carried with the conveyer away from said finger successively. In the event that a receptacle 3 has not been charged or has only been partly charged and is brought to rest 45

50 by the conveyer opposite finger 60 the latter will advance into the receptacle without being stopped by an article or goods opposing stop 62, (Fig. 10). The said advance of finger 60 will be sufficient to cause the grippers 66, 67 to engage the adjacent part 55 of the receptacle to grip it to the finger during the advance stroke of bar 75. When the receptacles have end flaps 3^a the grippers will grip said flaps. On the return stroke of bar 75 it will push bar 61 away from the receptacle and the finger 60 and the grippers that engage the receptacle will extract the receptacle 3 from the conveyer. Continued movement of the finger and grippers away from the conveyer will cause the 60

pins 66^a, 67^a to encounter the abutments 71, 72 to cause tilting of said fingers to release the receptacle which will encounter the stops 73, 74, causing discharge of the receptacle from the finger and grippers. The afore- 70 said operations of extracting a receptacle from the conveyer occur each time a receptacle is not charged sufficiently to prevent the grippers from engaging the receptacle to pull it away from the conveyer. 75

After the charged receptacles have passed with the conveyers from the extracting devices said receptacles may be removed from the machine in any desired or usual way. When the receptacles have end flaps the latter may be closed in any suitable manner. We have illustrated movable flap closers 83, 84, operated by arms 85, 86 connected by link 87 and actuated to rock by arm 88 operated by crank 89, in a well known manner. 80 Stationary flap closers are indicated at 90, 91, of a well known character. Pasting devices for the flaps 3^a are indicated generally at 92. 85

Our invention provides simple and effective means to assure that receptacles or cartons 3 discharged at the delivery end D of the machine will be properly charged, as required, to assure against the delivery of uncharged or partly charged receptacles 90 with the desired charged receptacles, thereby overcoming the disadvantage sometimes experienced with automatic packing machines of delivering improperly charged receptacles or cartons with charged ones. 100 100

Having now described our invention, what we claim is:

1. A packaging machine comprising supporting means for receptacles, means to charge the receptacles with articles, and devices to extract uncharged receptacles from the supporting means comprising means adapted to enter the receptacles, and grasp the same and remove the receptacles from the support, and an abutment opposing articles in the receptacle and the extracting devices to prevent the entry of the extracting devices into a charged receptacle. 110

2. A packaging machine comprising supporting means for receptacles, means to charge the receptacles with articles, a finger to enter the receptacles to engage articles therein, gripping means for the receptacles, associated with the finger, means to move the finger and gripping means toward and from the receptacles, and means to actuate the gripping means to release receptacles when the gripping means move with receptacles. 115 120

3. A packaging machine comprising supporting means for receptacles, means to charge the receptacles with articles, a finger to enter the receptacles to engage articles therein, gripping means for the receptacles associated with the finger, means to move the finger and gripping means toward and from 125 130

- the receptacles, and means to actuate the gripping means to release receptacles when the gripping means move with receptacles, and means to oppose articles in the receptacles to prevent the gripping means from engaging charged receptacles.
4. A packaging machine comprising means to support receptacles, means to charge the receptacles, and means to extract uncharged receptacles from the support including a finger to enter and engage articles in the receptacles, a gripper to engage the receptacles, means to move the finger and gripper toward and from the receptacle, and means opposing articles in the receptacles on the side opposite the finger to resist advance of said articles when engaged by the finger to prevent the gripper from grasping the receptacles.
5. A packaging machine comprising means to support receptacles, means to charge the receptacles, and means to extract uncharged receptacles from the support including a finger to enter and engage articles in the receptacles, a gripper to engage the receptacles, means to move the finger and gripper toward and from the receptacles, and means opposing articles in the receptacles on the side opposite the finger to resist advance of said articles when engaged by the finger to prevent the gripper from grasping the receptacle, and means to actuate the gripper when moved from the receptacle to release a receptacle.
6. A packaging machine comprising means to support receptacles, means to charge the receptacles, and means to extract uncharged receptacles from the support including a finger to enter and engage articles in the receptacles, a gripper to engage the receptacles and means to move the finger and gripper toward and from the receptacles, and means opposing articles in the receptacle on the side opposite the finger to resist advance of said articles when engaged by the finger to prevent the gripper from grasping the receptacle, means to actuate the gripper when moved from the receptacle to release a receptacle, and means to discharge receptacles from said gripper.
7. A packaging machine comprising means to support and charge receptacles, an abutment to oppose articles in the receptacle, and means on the side of the receptacle opposite the abutment and movable relatively thereto to enter the receptacles when unobstructed by articles therein and said abutment, and gripping means movable with the last named means to grasp receptacles and remove them from said support.
8. A packaging machine comprising a conveyer having means to retain receptacles, means to charge the receptacles, means to operate the conveyer, a reciprocatve finger adjacent to the conveyer to enter the receptacles thereon when unobstructed by articles in the receptacles, gripping means for the receptacles associated with said finger, means to cause the gripping means to release the receptacles, and means to cause charges in the receptacles to obstruct the finger within the receptacles to prevent the gripping means from engaging the receptacles.
9. A packaging machine comprising a conveyer having means to retain receptacles, means to operate the conveyer, a member at one side of the conveyer movable relatively thereto, said member having means to remove receptacles from the conveyer including a finger to enter the receptacles to engage full charges therein, and means to move said member toward and from the conveyer, said last named means including devices to permit movement of the last named means independently of said member when said finger engages full charges in the receptacles.
10. A packaging machine comprising a conveyer having means to retain receptacles, means to operate the conveyer, a member at one side of the conveyer movable relatively thereto, a finger carried by said member to enter the receptacles to engage charges therein, receptacle gripping means supported by said member, means to actuate the gripping means to release receptacles, and means to operate said member including devices to permit said operating means to move independently of said member when the finger engages full charges in the receptacles.
11. A packaging machine comprising a conveyer having means to retain receptacles, means to operate the conveyer, a member at one side of the conveyer movable relatively thereto, a finger carried by said member to enter receptacles to engage charges therein, a gripper movably supported by said member to engage receptacles on the conveyer, means spaced from the conveyer to actuate said finger to cause it to release receptacles, and actuating means for said member including devices to permit said actuating means to move independently of said member when the finger engages charges in the receptacles.
12. A packaging machine comprising a conveyer having means to retain receptacles, means to operate the conveyer, a member at one side of the conveyer movable relatively thereto, a finger carried by said member to enter receptacles to engage charges therein, a gripper movably supported by said member to engage receptacles on the conveyer, means spaced from the conveyer to actuate said gripper to cause it to release receptacles, and actuating means for said member including a reciprocatve bar having a slot, a projection on the member received in said slot, a spring connecting said bar and member, and means to actuate said member.

13. A packaging machine comprising a conveyor having means to retain receptacles, means to operate the conveyor, spaced charging means to insert part charges in the receptacles, a reciprocative finger spaced from the charging means to enter receptacles, gripping means for the receptacles associated with the finger, means to cause the gripping means to release receptacles, and means to move the finger and gripping

means toward and from the conveyor including means to permit the finger to be arrested in its movement toward a receptacle when the finger encounters a full charge in a receptacle.

Signed at New York city, New York,
